UNITED STATES PATENT OFFICE.

PATRICK K. HARDIN, OF CHICAGO, ILLINOIS.

VALVE DEVICE.

SPECIFICATION forming part of Letters Patent No. 629,249, dated July 18, 1899.

Application filed August 20, 1898. Serial No. 689,182. (No model.)

To all whom it may concern:

Be it known that I, PATRICK K. HARDIN, a citizen of the United States of America, and a resident of Chicago, county of Cook, and State of Illinois, have invented certain new and useful Improvements in Valve Devices, of which the following is a specification.

My invention relates in general to valve devices and in particular to fluid-valves adapted for use in regulating the flow of fluids under pressure.

Prominent objects of my invention are as follows, viz: to arrange for the automatic closure of the valve upon the removal of the force which has opened it and for its automatic maintenance in a closed condition; to utilize the fluid under pressure as the sole agency in thus causing the automatic closure of the valve and maintaining the same in a closed condition; to render it impossible to tie or wedge or otherwise hold the valve open, except by the direct application of the opening force; to simplify the construction of the device as much as possible, and in so doing to dispense with all undesirable appliances—such as levers, handles, eccentrics, stuffing-boxes, springs, washers, and the like—in its construction; to absolutely prevent pounding or hammering in the closing of the device; to render it impossible for the fluid or other matter under regulation to injure or inconvenience the hand or hands in operating the valve; to allow access to the interior of the valve and the removal, repair, or replacement of parts therein while the device is attached for service and in open communication with the fluid under pressure; to render unnecessary the use of tools, wrenches, and the like in thus gaining access to the interior of the device and also in attaching it to the pipe or main for service and detaching it from the same; to avoid the use of rubber or like material on or in connection with the valve-seat; to prevent rot, decay, corrosion, and the like within the device and also to prevent injurious results from the effects upon it of variations in the temperature, nature, or composition of the fluid under regulation, and to accomplish the above-mentioned results in a simple, economical, effective, and inexpensive manner.

To the attainment of the foregoing and other

desirable ends my invention consists of matters hereinafter fully set forth.

In the accompanying drawings, Figure 1 is 55 a view, partly in elevation and partly in longitudinal section, of a valve device embodying my invention. Figs. 2 and 3 are cross-sections of the same, taken on lines 2 2 and 3 3, respectively, in Fig. 1; and Fig. 4 is a view 60 of a detail of construction.

In the drawings I have illustrated my invention applied to a basin-cock—that is to say, to a cock or faucet particularly adapted for use in connection with washbasins. I desire 65 it to be understood, however, that in so doing I do not intend to limit the invention to that application of it, for it can be applied equally well to any one of a great variety of valves, cocks, faucets, and the like having many and 70 diversified uses.

In thus illustrating my invention embodied in a basin-cock I exhibit an operative device and at the same time afford an illustration of one of the many uses to which it is particularly and peculiarly adapted.

In the arrangement illustrated in the drawings the water or other fluid under pressure is supplied from any suitable source by way of a supply-pipe P. Thence it flows into a 80 valve-chamber G, which forms the lower end of the basin-cock, and communicates with the interior of the supply-pipe P by way of a suitable passage or opening g at its lower end. The valve-chamber is conveniently provided 85 by a suitable shell or casing G', preferably of cast metal, such as brass, while the passage or opening g into the supply-pipe P is conveniently provided by a neck g', formed at the lower end of the shell or casing G'. 90

The shell or casing G', providing the valve-chamber G, is shown attached to the supply-pipe P by a suitable coupling m, which is arranged to screw over the threaded end of the supply-pipe P and also over the neck g' of the 95 shell or casing G'.

The fluid under regulation is controlled so as to allow or prevent its passage or flow from the valve-chamber G by means of a suitable outlet or port N, arranged at the upper end 100 of such chamber, and a valve F, adapted to coöperate with an outwardly-facing valve-seat H, formed at the end of such port N, so as to open and close the latter. (By an "out-

wardly-facing valve-seat" is meant one which faces the fluid as the latter approaches it.) In this way the valve F will always be forced in the direction of flow of the fluid and so will be continually subjected to pressure or force tending to force and hold it against or upon its seat. As a result the port N, and therefore the device, will normally and automatically maintain itself in a closed condition, except when the valve F is subjected to pressure sufficient to force it away from its valve-seat, and will automatically close itself upon the removal of such pressure.

Any suitable type or construction of valve could be employed, as the valve F, for thus automatically closing the port N and retaining the same closed by the action of the fluid in the device. I desirably employ a ball-valve, however, such as is shown in the drawings, for the reason that it is simple, inexpensive, and efficient and very difficult to injure and very easy to repair or replace.

The ball F is desirably made larger than the inlet-passage g of the valve-chamber G, in which way all danger of its falling into the supply-pipe P and so becoming lost or clogging the latter is removed. The ball F could be made of any suitable material, such as rubber or the like; but as a matter of specific improvement I construct it of cork. By so doing I avoid the necessity of employing washers, packing, or the like upon the valve-seat, as the cork naturally makes a tight joint in seating itself. At the same time I provide a valve which will float and so assist the fluid-pressure in causing the automatic closure of the device and will, in fact, cause such automatic closure by its floating qualities, even though the fluid-pressure be so light as to be almost negligible. The ball F could be depressed so as to open the port N and allow the flow of the fluid under regulation by any suitable mechanism adapted for the purpose. As a preferred arrangement, however, it is operated by the mechanism illustrated in the drawings, which mechanism I consider a matter of further and specific improvement.

The mechanism illustrated involves a reciprocating plunger E, which is positioned 50 above the valve-chamber G and has its lower end or foot normally resting upon the ball F, so that its depression to a greater or less degree instantaneously causes a corresponding depression of the ball F and opening of the port N.

The plunger E is confined and reciprocates within a suitable substantially cylindric plunger-chamber L, arranged above the valve-chamber G. To prevent its wabbling or inclining laterally and to effectively guide and center it, the plunger E is provided, near its upper end, with a number of laterally-extending webs K, which are constructed to allow its easy reciprocal movement within the chamber L.

The chamber L is provided by a suitable shell or casing O, which also desirably pro-

vides the port N and valve-seat H by having the same formed at its lower end. It is suitably attached to the upper end of the casing G, as by being screw-threaded thereto, as shown, in which way it can be readily and easily attached and detached. It is desirably composed of metal, preferably brass, and when so composed can be easily made by casting the metal into the desired shape or form.

The too sudden seating of the valve F, and therefore the hammering or pounding within the device, is prevented by subjecting the valve F to the influence of an air-cushion A, which operates to retard or dampen its upward movement when it has been released from its opening pressure and is being acted upon by the fluid to automatically close the device. As a simple and convenient arrangement the air-cushion A is formed by the air within a suitable air-bulb A'. The latter is desirably positioned above and screw-connected with the plunger-casing O, in which way it can be easily and quickly and without the use of tools attached for service and detached in order to permit access to the plunger E or the removal and replacement thereof, as desired.

While the valve-actuating plunger E could be actuated so as to depress the valve F by any suitable means, it is as a matter of specific improvement actuated by a push-spindle B, having a push-button C, which can be readily depressed by the fingers or thumb and which is arranged so that when so depressed it correspondingly depresses the plunger E and the valve F. In this way the device can be opened simply by the pressure of one or more of the fingers or of the thumb and can be held open as long as desired by such pressure; also, when such opening pressure is removed the elevation of the valve F and the plunger E will operate to restore the push-button C to its original position. As a convenient arrangement the push-button C is arranged to work in a suitable opening formed in the top of the air-bulb A', so as to properly center and guide the push-spindle B. Inasmuch as the push-button C does not fit tightly within the opening in the top of the air-bulb A', the air, and consequently the fluid, would escape through that opening when the device is opened. This is prevented by the interposition of a flexible and elastic diaphragm D in such position as to exclude the fluid from access to the opening. As a simple arrangement the diaphragm D is positioned between the upper end of the plunger E and the lower end of the push-spindle B,

and when so positioned causes the air-cushion A to act upon the plunger E and therethrough upon the valve F. To promote efficient action and also to prevent puncture of the diaphragm D, the lower end of the push-spindle B and the upper end of the plunger E are respectively provided with slightly-convex heads B' and I. The diaphragm D is

desirably held in position by interposition between the lower edge of the air-bulb A' and the upper edge of the plunger-casing O, in which way it can be easily reached or removed and replaced by unscrewing the air-bulb A'. The diaphragm D can be made of any suitable flexible and elastic material, such as substantially pure rubber, rainbow-packing, and the like. It will be seen that by this arrangement the necessity of stuffing-boxes and the like is avoided, and at the same time the temperature of the fluid is not communicated to the push-button C, and so no inconvenience is experienced by reason of the latter being too hot or cold for comfort.

From the plunger-chamber L, into which it passes from the ports N, the fluid can flow into any suitable pipe or other device, in accordance with the use to which the device is put. In the basin-cock illustrated it passes into a suitable nozzle or spout R, which is attached to and at one side of the plunger-casing O in any well-known way.

It will be understood that certain changes, alterations, or variations could be made in the construction herein shown and described without departing from the spirit of the invention.

It will be seen that my invention provides an effective, simple, and inexpensive device, and contains the various advantages sought for in devices of its class.

What I claim as my invention is—

1. A valve device comprising a casing providing an inlet-chamber; a ball-valve controlling the outlet of said chamber; a reciprocating plunger acting against the ball-valve; a casing containing the plunger and serving as a guide to insure the proper reciprocation thereof; a flexible and elastic diaphragm

which is secured in position to rest upon the upper end of the plunger, but which is not secured or attached thereto; a casing providing an air-chamber above the diaphragm; and a loose push-spindle arranged within the casing providing the air-chamber, and having its upper end extended through the top of said casing, and its lower end acting upon the plunger through the medium of the diaphragm. 45

2. A valve device comprising a casing providing an inlet-chamber; a ball-valve controlling the outlet of said chamber; a reciprocating plunger acting against the ball-valve and provided with a convex disk-shaped head and also with laterally-extending webs below 50 said head; a casing detachably secured to the upper end of the inlet-casing and provided with an interior bore which contains said plunger and serves as a guide for the same; a flexible and elastic diaphragm resting upon 55 the head of the plunger, but not secured thereto; an air-chamber providing casing which is detachably secured to the upper end of the casing containing the plunger, and which holds the diaphragm in position by 60 clamping the same between itself and the last-mentioned casing; and a loose push-spindle arranged within the casing providing the air-chamber and having the upper end extended through the top of said casing, and 65 the lower end acting upon the plunger through the medium of the diaphragm and guided by a guide formed at the lower end of said casing. 70

Signed by me, at Chicago, Illinois, this 17th day of August, 1898.
